UNITED STATES PATENT OFFICE.

JOHANN CARL FRIEDRICH ALBERT SCHÜTTE, OF ALTDORF, SWITZERLAND.

APPARATUS FOR PRODUCING SHEETS AND SIMILAR ARTICLES ELECTROLYTICALLY.

Application filed October 6, 1927, Serial No. 224,432, and in Germany December 29, 1925.

The present invention relates to improvements in apparatus for electrolytic production of sheets and similar articles from ores containing metals, metal waste and the like, and its primary feature consists in providing special agitating means for the purpose of imparting to the electrolyte a strong circulation and a distinct direction of flow in order to obtain dense and uniform deposition of the metal. This motion of the electrolyte can be effected by any suitable means, for instance by means of shafts provided with blades or equivalent stirring devices. The ore or the like to be treated is deposited in a cage, through which the electrolyte is passed, dissolving the metal and precipitating it in the desired form on the cathode.

In order to fully describe the invention and to explain the mode of operation and the details of the apparatus, reference is had to the drawings in which

Figure 1 is a vertical section through the apparatus;

Figure 2 a horizontal section on line 2—2 of Figure 1, and

Figure 3 a vertical section through a modified form of the apparatus.

The apparatus shown in Figures 1 and 2 consists of a circular or polygonal vat 1 made of wood, stoneware or the like, whose inner walls are covered with a lead-lining 2. The latter constitutes the cathode, electric current being admitted to it through a lead 4. On the bottom of the vat is provided a lead plate 4^a, to which no current is supplied, and which plate is placed in such a manner that a hollow space remains underneath it, within which the sludge formed during the electrolytical treatment, is collected. A shaft 6 provided with blades 5 is arranged within the vat 1 and journaled in the cover 7 of the said vat. Concentrically to the shaft 6 are arranged an inner cylinder 8 and an outer cylinder 9 made of lead or any other suitable metal, said cylinders being provided with perforations 8' and 9' respectively. The two lead cylinders 8 and 9 are firmly mounted between two circular discs 10 and 11 the upper one of which is provided with a neckring 10', by means of which the cage formed by the cylinders 8, 9 and the discs 10, 11 can be suspended from a socket or hollow shaft 13 by pins 12, said shaft being rotatably mounted in the cover 7. At the upper end

of the shaft 13 a bevel gear wheel 14 is rigidly keyed, meshing with a bevel gear wheel on a shaft 15. The latter is journaled in a bearing support 17 mounted on the cover 7 of the vat. On the outer end of the shaft 15 is mounted a belt pulley 18 and it is driven by a belt 19 from a belt pulley 20 arranged on the transmission shaft 21. On the shaft 6 mounted to rotate in the socket 13 is keyed a bevel gear wheel 22, meshing with another bevel gear wheel 24 mounted on a shaft 23. The shaft 23 is journaled in a support 25 likewise arranged on the cover or lid 7 of the vat. The said shaft is provided at its outer end with a belt pulley 26 and derives its rotary movement through a crossed belt 27 and belt pulley 20 arranged on the transmission shaft 21. Upon the cage 8, 9, 10 and 11 a circular disc 29 of copper is mounted, on which slides a copper brush 30 connected with the positive pole of a source of electric current, while the lead lining 2 of the vat, serving as cathode, is connected with the negative pole of said source of current by conductor 4.

The operation of the apparatus is as follows:

The ore, material containing ore or waste 31 to be treated, is placed between the two concentrically arranged cylinders 8 and 9. After the electric current is connected the electrolyte thoroughly agitated by means of the blades 5 provided on the rotating shaft 6 is uniformly admitted to the ore or the like through the perforations 8' in the cylinder 8. In order to produce the uniform dispersion of electrolyte, the cage 8, 9, 10, 11 containing the ore or the like is rotated too, namely according to Figure 1 in the same direction as shaft 6 but at a different speed. The electrolyte rich in metal is passed through the openings 9' in the lead cylinder 9 and in consequence of the rotary movement 100 of the cage 8, 9, 10, 11 it is passed uniformly to the cathode 2 where a uniform deposit of the metal is obtained.

According to the modification shown in Figure 3 the cylinders 8 and 9 are suspended independently of one another, and the outer cylinder 9 is secured to a disc 33 provided with a sleeve 32, by means of which and a pin lock 34 it is connected with the hollow shaft 13' that is rotatably mounted on the lid 7. A hollow shaft 35 is rotatably mounted within the hollow shaft 13'. To the

shaft 35 is connected, by pins 36, the hollow boss extension 61 of the plate 60 of the inner cylinder 8. The plate 60 receives current from the plate 33 through a sliding spring 35^a. The shaft 6 extends through the hollow shaft 35. The shaft 6 and the cylinders 8, 9 are actuated by the transmission shaft 21, viz: the shaft 6 through the bevel gear wheels 22, 24, the belt pulleys 26 and 28 and 10 the crossed belt 27; the cylinder 8 through a bevel gear wheel 37 mounted on the hollow shaft 35 connected with said cylinder, said wheel 37 meshing with a bevel gear wheel 38 provided on a shaft 39 journaled in the bearing support 38^a. The shaft 39 is driven by the shaft 40 through a transmission gearing 40, 41. The cylinder 9 is actuated by the bevel gear wheels 14, 16 through the belt pulleys 18, 20 and the belt 19. A clutch 42 permits the shaft 40^a to be disconnected from the driving pulley 26.

According to the modification represented in Figure 3 the cylinders 8 and 9 are independent of one another. In order to stop 25 the cylinder 9 while the cylinder 8 and shaft 6 continue their rotation, idle pulleys 18' and 20' respectively are arranged on the shafts 15 and 21 respectively. If, however, it is desired to stop the cylinder 8 while the 30 cylinder 9 and shaft 6 continue to rotate, the clutch 42 provided on the shaft 23 for this purpose, is disengaged. It is obvious that both cylinders 8, 9 can be held stationary, while the shaft 6 is moving. If it is 35 desired to rotate the cylinders 8 and 9 in the same direction, the crossed belt 27 is removed and replaced by an open one.

Through the arrangement according to the invention a high density of the decomposed 40 metal is attained, and through the strong action of the moving electrolyte a fine and smooth structure on the cathode. This arrangement will dispense with the tedious and expensive melting and metallurgical processes hitherto always employed in the manufacture of sheets of metal, and these latter 45 are produced in a finished state in a single operation.

I claim:

50 1. In apparatus for producing sheets and similar articles electrolytically, the combination with a casing of any suitable form, serving as cathode, means for stirring the electrolyte and arranged in said casing, an 55 anode-casing containing the ore or the other material to be treated electrolytically, said anode-casing surrounding the stirring means and having perforations through which the electrolyte acting on the ore or the like is forced by said agitating means, and means 60 for actuating said agitating means.

2. In apparatus for producing sheets and similar articles electrolytically, the combination with a casing of any suitable form, serv-

ing as cathode, and provided on its inner 65 surface with a lead-lining, a power-actuated rotating agitating device provided with fans and arranged in said casing, a perforated metallic anode-casing serving as container for the material to be treated electrolytically, 70 said anode-casing consisting of an inner and outer wall provided with perforations and provided with a bottom plate and lead plate for the purpose of leading the current to said anode-casing, said casing adapted to be rotated about the agitating device in a direction opposite to the agitating device, and means for actuating the agitating device and the anode-casing.

3. In apparatus for producing sheets and 80 similar articles electrolytically, the combination with a metallic cathode connected with the positive pole of a source of current, a power-actuated rotary agitating device arranged within the said cathode, an anode- 85 casing containing the ore or the like to be treated electrolytically, said casing adapted to be rotated about the agitating device and rotating in the direction opposite to that of the agitating device, and means for actuating 90 the agitating device and the anode casing.

4. In apparatus for producing sheets and similar articles electrolytically, the combination with a casing of any suitable form, 95 serving as cathode and provided on its inner surface with a metallic lining, a power-actuated rotary agitating device arranged within said cathode, an anode-casing serving as container for the ore or the like to be treated electrolytically, said casing adapted to be rotated about the agitating device in a direction opposite to that of the said agitating device, means for actuating the anode- 100 casing, a bevel gear wheel arranged on the upper end of the agitating shaft, a second bevel gear-wheel meshing with said bevel gear-wheel and being driven by a crossed belt.

5. In apparatus for producing sheets and 110 similar articles electrolytically, the combination with a casing serving as cathode and provided on its inner surface with a lead lining, a power-actuated agitating device arranged within said cathode-casing, an 115 anode-casing containing the ore or the like to be treated electrolytically, said casing being adapted to be rotated about the agitating device in a direction opposite to that of the agitating device, a bevel gear-wheel connected with said anode-casing by means of two pins, said gear-wheel being actuated by another bevel gear-wheel which is driven by means of an open belt, and means for actuating 120 the agitating device.

In testimony whereof I have signed my name to this specification.

JOHANN CARL FRIEDRICH ALBERT SCHÜTTE.
